UNITED STATES PATENT OFFICE.

JOSEPH WILSON, OF NEW YORK, N. Y.

DESIGN FOR A GLASS PITCHER, &c.

SPECIFICATION forming part of Design No. 28,282, dated February 15, 1898.

Application filed December 16, 1897. Serial No. 662,226. Term of patent 7 years.

To all whom it may concern:

Be it known that I, JOSEPH WILSON, a citizen of the United States, residing at New York, (borough of Brooklyn, county of Kings,) 5 in the State of New York, have invented and produced a new and original Design for a Glass Pitcher and Like Receptacles, of which the following is a specification, reference being had to the accompanying drawing, forming a part thereof, which represents a side elevation of a pitcher embodying the features 10 of my design.

The design consists in a panel A, decorated with "punties" B, prismatic panels C at each side of the punty-panels, and box-panels D, 15 crossing the punty and prismatic panels.

I claim—

The design for a glass pitcher and like receptacles, herein shown and described.

JOSEPH WILSON.
